UNITED STATES PATENT OFFICE.

FRANK SKINNER, OF PHILADELPHIA, PENNSYLVANIA.

PIPE-HANGER AND SHIELD FOR BICYCLE-RIDERS.

SPECIFICATION forming part of Letters Patent No. 605,142, dated June 7, 1898.

Application filed October 13, 1897. Serial No. 655,091. (No model.)

To all whom it may concern:

Be it known that I, FRANK SKINNER, a citizen of the United States, residing at Philadelphia, (Overbrook,) in the county of Philadelphia, State of Pennsylvania, have invented a new and useful Improvement in a Pipe-Hanger and Shield for Bicycle-Riders, of which the following is a specification, reference being had to the accompanying drawings.

10 The object of my invention is a device whereby a tobacco-pipe bowl furnished with a flexible stem is combined by means of a proper set-off with a shield to protect the garment of the user, said shield to serve as a 15 club-badge. I may utilize the badges at present in use for my purpose.

Referring to the drawings, Figure 1 is an elevation of the device, giving a view from the front, while Fig. 2 is the same elevation 20 exhibiting a view from the back. Fig. 3 is a side elevation of the pipe, showing the shield B and the loop C, by which it is attached to the pipe-bowl A. Fig. 4 is a plan view of the loop C and its engagement with the shield B 25 by means of the hooks E E.

Like letters indicate like parts throughout the figures.

A is the pipe-bowl, grooved with the annular groove D, into which is fitted the loop C, 30 said loop being preferably a piece of resilient wire having its ends E E bent back upon themselves to form hooks to engage with the slot F in the shield B. A small space is left between said hooks in order that said loop may

be contracted sufficiently to allow said hooks 35 to engage with said slot. Said loop expands of its own resiliency, and by this means said loop and the pipe-bowl carried in same may be attached to or detached from said shield. Said shield may be used as a badge, bearing 40 inscriptions, as at G in Fig. 1, and on that account it is desirable that its face be as free from objectionable features as possible. H represents the pin by which said badge is attached to the garment. 45

The slot F, on account of its being a small opening, does not disfigure the face of the shield. In fact, badges at present in use among wheelmen may be utilized by simply having the slot F cut in them. 50

Having now described my invention, what I claim, and desire to secure by Letters Patent, is—

In combination a badge, acting as a shield to protect the garment and furnished with 55 means for being attached to said garment, a tobacco-pipe bowl provided with a horizontal annular groove, and a removable, resilient, open, wire loop, said badge and bowl being connected by means of said wire loop, which 60 engages with said groove and by its hooked ends with a slot in said badge, substantially as described.

FRANK SKINNER.
